UNITED STATES PATENT OFFICE.

WILLIAM COUGHLAN, OF BALTIMORE, MARYLAND.

IMPROVEMENT IN SODA-FOUNTAINS.

Specification forming part of Letters Patent No. 58,608, dated October 9, 1866.

To all whom it may concern:

Be it known that I, WILLIAM COUGHLAN, of Baltimore, in the county of Baltimore and State of Maryland, have invented a new and useful Improvement in Soda-Water Fountains; and I do hereby declare the following to be a full, clear, and exact description of the same, sufficient to enable one skilled in the art to which the invention appertains to make use of it, reference being had to the accompanying drawings, which form a part of this specification, and in which my invention is represented by a central vertical section.

This invention is an improvement on my soda - water fountain patented October 25, 1853, in respect of the mode of gaging the amount of aerated water admitted into the fountain in charging it by means of placing the blow-off cock at that level; and, secondly, an arrangement by which the fountain can be used in a vertical or inverted position.

In the drawings, A is the fountain; B C, the ears or studs on the sides, by which it is suspended from the bail D. F is a collar on the upper part of the fountain, into which screws the lower end of the faucet E, to whose upper end is attached the pipe from the machine where the water is charged with carbonic-acid gas.

The faucet E being opened, and the pipe from the machine being attached, water impregnated with gas is admitted to the fountain, the air contained therein escaping, with some gas, through the opening J in the stud C, the screw-valve I being unclosed for that purpose. When the liquid contents arrive at the level of the opening J, it is indicated by the escape of water at that point, and, the valve I being closed, a further quantity of carbonic-acid gas is introduced above the water, when

the fountain is sufficiently charged, the spigot G closed, the pipe detached from the faucet E, and the fountain is ready for transportation to the place where it is to be used.

The tube H is screwed into the lower end of the faucet E when the fountain is to be used in the vertical position shown in the figure, so that the pressure of the air will force the water from near the bottom. Water reaches the level of the lower end of the tube.

Where the fountain is expected to remain charged a considerable length of time, with only occasional use, it may be inverted and the tube dispensed with, the contents being drawn through the faucet E, the water being against that end and the gas occupying the upper position against what was formerly the bottom of the fountain.

In use the connection of the pipe through which the soda is drawn is made to the outer end of the faucet E.

Having described my invention, what I claim therein as new, and desire to secure by Letters Patent, is—

1. The valve I and opening J in the stud C at the side of the fountain, at or near the desired level, to act as a gage and also as a blow-off opening for the discharge of the air from the fountain, substantially as described.

2. The auxiliary tube H, attachable or detachable from the faucet, to permit the fountain to be used in the upright or inverted position, substantially as described.

To the above specification of my improved soda-water fountain I have signed my hand this 14th of August, 1866.

WM. COUGHLAN.
